R. SEELEY.

WING CONSTRUCTION FOR BIPLANES.

APPLICATION FILED APR. 14, 1913.

1,096,567.

Patented May 12, 1914.

UNITED STATES PATENT OFFICE.

RICHARD SEELEY, OF JOLIET, ILLINOIS.

WING CONSTRUCTION FOR BIPLANES.

1,096,567.

Specification of Letters Patent. Patented May 12, 1914.

Application filed April 14, 1913. Serial No. 761,008.

To all whom it may concern:

Be it known that I, RICHARD SEELEY, a citizen of the United States of America, and a resident of Joliet, county of Will, and 5 State of Illinois, have invented certain new and useful Improvements in Wing Construction for Biplanes, of which the following is a specification.

This invention relates to the construction 10 of wings or planes for aircraft employing a plurality of such superimposed planes.

The main objects of the invention are to provide an aeroplane construction for superimposed segmental planes combined with 15 struts, stays, and tensioning devices which may be disassociated and reassembled without readjustment of the tensioning devices; and to provide a pair of superimposed sectional planes and connecting struts adapted 20 to both separate the planes and to connect the adjacent segments of each plane.

The drawing is a fragmentary sectional view in front or rear elevation of the spars 25 or frames of a pair of aeroplanes and their connections.

The ribs and coverings of the wings and other details of construction not relating directly to the present invention are omitted.

Biplanes are frequently so constructed 30 that their wings or aeroplanes may be separated in sections for convenience in shipment. The struts, stay wires, and other connections between said planes and sections of the planes have heretofore been so constructed 35 that each time the aircraft is assembled for use it is necessary to readjust the connections, such as with turnbuckles in the stay wires, for the reason that to disassemble the device it is necessary to operate 40 the turnbuckles to release the tension on the stays or braces.

The present invention provides an aeroplane with a sectional wing construction and connections which when once properly adjusted 45 may be disassociated or assembled with little or no readjustment of the stays or other connections.

Referring to the drawing, a pair of planes 1 and 2 are shown, each consisting of a 50 plurality of sections connected together by struts 4 passing through eyes 5 in metallic fixtures 6 riveted or bolted to the main spars 7 of the wing frame. The struts or stanchions 4 are preferably hollow metallic tubes 55 provided with metallic plugs 8 and 9 seated in and secured to the ends of the tubes.

These plugs pass through the eyes 5 in the fixtures 6 and have in their ends retaining pins or cotters 10 which prevent the struts from becoming accidentally disconnected 60 from the spars 7. Secured to the struts just inside of the planes are metallic guy rings or collars 11 carrying rings 12 or other suitable devices to which the diagonal tension members or braces 13 may be secured. 65 The braces 13 are, as usual, provided with turnbuckles 14 by means of which their tension may be regulated, and serve the usual purpose of making the wing constructions rigid from end to end. 70

The upper plugs 8 may be rounded as designated by the numeral 15, but the ends of either these plugs or the lower ones are preferably conical, as the lower ones are shown designated by the numeral 16. The 75 conical ends of the plugs permit the struts 4 to be wedged into connection with the fixtures 6 on reassembling the device, without any adjustment of the turnbuckles 14.

To disassemble the aeroplanes, the pins 80 10 are first removed and then the plane sections may be freely removed as indicated in the drawing, the lower right hand segment 3 being thus shown disconnected from the right hand strut 4. The stays 13 may then 85 be rolled on the struts 4 without being disconnected therefrom, but even if they are disconnected it is unnecessary to manipulate the turnbuckles 14 either for removing the wing segments or for any other purpose. 90 Similarly in reassembling the device, the upper rounded ends 15 of the plugs 8 in the struts 4 are inserted through the eyes 5 in the metallic fitting 6 to the upper plane 1, and then the sections 3 of the lower plane 2 95 are fitted on the lower plugs 9, the pointed ends 16 of said plugs permitting the latter to be wedged through the openings 5 in the fittings 6. Finally the pins 10 are replaced 100 and thus the planes are again assembled ready for use.

From the foregoing it may be seen that the operation of assembling the planes need require very little if any adjustment of the turnbuckles 14.

Although but one specific embodiment of 105 this invention has been herein shown and described, it will be understood that numerous details of the construction shown may be altered or omitted without departing 110 from the spirit of this invention as defined by the following claims.

2
I claim:—

1. In a wing construction for aeroplanes, a pair of superimposed wing spars, eyes in said spars, a pair of struts connecting said spars and passing through said eyes, diagonal braces connecting said struts, and each of said struts having a wedge shaped end whereby they may be removed from or wedged into said eyes in such manner as to enable the parts to be separated and assembled without readjusting the length of said braces.

2. In a wing construction for aeroplanes, a pair of superimposed wing spars, eyes in said spars, a pair of struts connecting said spars and passing through said eyes, diagonal braces connecting said struts, and each of said struts having a conical end whereby they may be removed from or wedged into said eyes in such manner as to enable the parts to be separated and assembled without readjusting the length of said braces.

3. A wing construction for aeroplanes, comprising a pair of superimposed planes, each plane consisting of a plurality of sections having eyes in their ends, struts passing through said eyes, and diagonal braces connecting said struts, said braces including turnbuckles, said struts having pointed ends whereby they may be removed from and wedged into said eyes without readjustment of said turnbuckles.

4. A wing construction for aeroplanes, comprising a pair of superimposed planes, each plane consisting of a plurality of sections having eyes, and hollow struts having plugs in their ends passing through said eyes, said plugs having pointed ends.

Signed at Chicago this 12th day of April 1913.

RICHARD SEELEY.
